United States Patent Office

Des. 217,845

Patented June 23, 1970

217,845

LADIES HANDBAG LOCK

David Damast, 522 Shore Road,
Long Beach, N.Y. 11561

Filed May 29, 1969, Ser. No. 17,404

Term of patent 3½ years

Int. Cl. D8—03

U.S. Cl. D8—129

Fig. 1.

Fig. 2.

Fig. 4.

Fig. 3.

FIG. 1 is a front perspective view of a lady's handbag lock showing my new design with the parts in a separated position;

FIG. 2 is a top plan view of the assembled parts;

FIG. 3 is a front elevational view thereof; and

FIG. 4 is a side elevational view thereof.

I claim:

The ornamental design for a ladies handbag lock, substantially as shown.
